Primary Examiner — Katherine Glennon*(74) Attorney, Agent, or Firm* — Suzanne Kikel, Patent Agent(57) **CLAIM**

The ornamental design for a garage door sensor, as shown and described.

DESCRIPTION

FIG. 1 is a front perspective view of a garage door sensor in the environment of its use, showing my new design.

FIG. 2 is a front perspective view of the garage door sensor shown in FIG. 1.

FIG. 3 is a front view thereof.

FIG. 4 is a rear view thereof.

FIG. 5 is a left side view thereof.

FIG. 6 is a right side view thereof.

FIG. 7 is a bottom plan view thereof; and,

FIG. 8 is a top plan view thereof.

The broken lines shown in FIG. 1 represent environmental structure forming no part of the claimed invention.

The broken lines depict portions of the garage door sensor that form no part of the claimed design.

1 Claim, 8 Drawing Sheets(56)
